Patent expires April 21, 1964

12 Claims. (Cl. 315—171)

1

The present invention relates to circuits for operating an electric discharge device of the kind wherein the voltage needed to start or restart the discharge greatly exceeds the open circuit voltage of the supply from which the device is fed. More particularly the invention is concerned with a circuit for operating a high pressure mercury vapour lamp.

In order to initiate the discharge in air-cooled mercury vapour lamps in their cold condition it is usual to apply a high voltage, such as that obtained from a Tesla coil, across the electrodes. This causes a glow discharge to take place and so enable the main discharge to be initiated. Such a high voltage discharge may fail to strike the lamp when it is in the hot condition and the pressure of the mercury vapour is high. Moreover, with lamps of high operational wattages with relatively large electrode spacing such a discharge as that produced by a Tesla coil is not capable of striking the lamp, even in the cold condition when the pressure of the filling (comprising the mercury vapour and a small amount of a rare gas) is only a few millimetres. Even if the lamp is capable of being struck in the cold condition by the discharge from a Tesla coil, the lamp may be required to be brought into operation soon after switching off, before the temperature has fallen and while the pressure of mercury vapour is still high, so that the Tesla coil cannot be employed to strike it. Such an operational requirement would exist in the case of search-lights employing mercury vapour lamps which have to be switched on rapidly soon after being extinguished.

In a practical example of a mercury vapour lamp employed in a searchlight, the lamp when running normally from, say, a 110 volt D. C. source passes a current of at least 140 amps. and dissipates a total power of at least 11.5 kilowatts. The pressure of the filling when cold is only a few millimetres but when the lamp has attained its normal running temperature the pressure is about fifteen atmospheres.

The present invention provides a method by which a mercury vapour lamp is started, either in the hot or cold condition, by means of a high voltage pulse capable of causing a high voltage spark to occur between the lamp electrodes. According to the invention, an operating circuit for a high pressure mercury vapour lamp comprises connections for applying the normal running voltage to the lamp electrodes, a resonant circuit connected to the electrodes and means for generating and applying the high voltage pulse

across the resonant circuit and electrodes, the decrement of the resonant circuit being such that the spark will persist for sufficient time to enable the main discharge to establish itself.

5 In the particular case of the lamp previously referred to, a voltage impulse with a peak value of approximately 20 kv. is required when the lamp is in the hot condition to break down the interelectrode gap of the lamp and for the resulting high voltage arc to be instrumental in striking the lamp a maximum current, in the arc, of about 8 amps. is required initially. This impulse of current is produced by the discharge of a large condenser. However if the arc was 10 produced by the direct discharge of such a charged condenser through the lamp, the duration of the arc would be no longer than a few micro-seconds, and the main low voltage, high current discharge would have no opportunity to establish itself before the end of the arc and therefore the lamp would merely flash and go out again. It is found that with the lamp considered, it is necessary for the arc to be maintained for about 35 micro-seconds to ensure that 15 the lamp is properly struck, whatever its conditions of temperature and pressure. This is achieved by employing an oscillatory discharge having a frequency of about 345 kc./s. The maximum voltage across the lamp and the maximum current in the arc, at the commencement of the discharge, were approximately 20 kv. and 8 amps., respectively, and the decrement of the circuit was such that the peak oscillatory voltage 20 across the lamp had fallen to a few thousand volts after about 35 micro-seconds, the arc discharge still persisting.

25 The invention can be put into practice in various ways, and one preferred arrangement will now be described by way of example with reference to the accompanying diagrammatic drawing which shows a circuit diagram of the starting and running arrangements of a high pressure mercury vapour lamp intended for use in a searchlight.

30 The mercury vapour lamp A has the main 110 volt D. C. supply connected across it via the contacts of a main contactor O and an H. F. choke N. Also connected across the lamp is the circuit for generating the surge of high frequency, comprising the condenser C₁, transformer T, low capacity chokes L₁ and L₂, condenser C₂, spark gap G and inductance L₃.

35 The mercury switch D which controls the charge and discharge of condenser C₁ comprises 55 two sets of contacts S₁ and S₂ and is mounted

upon a plate capable of partial rotation and pivoted about its lowest corner. The switch is operated to charge or discharge C_1 by partial rotation of the plate caused by an iron armature EA, secured to the plate, which is mounted between the poles of an electromagnet E having a current limiting resistance R_1 in series with its winding. The switch is normally held in one position by means of a spring P, energisation of the electromagnet causing it to assume the alternative position.

Relay F incorporated in the control circuit is magnetically operated and is of the type in which on successive energizations of an operating circuit, a circuit alternately is made and broken between a pair of contacts, the condition set up at one energization remaining until the next. The operating circuit is connected between the terminals T_1 and the contacts are connected one to each of the terminals T_2 . A circuit is thus made and broken between the terminals T_2 on alternate energizations of the operating circuit by application of a voltage across the terminals T_1 . Relays of this type are described in British patent specification No. 257,632. A $4 \mu f$. condenser C_4 is connected across the terminals T_2 to prevent sparking when the contacts open.

The push button control switch B comprises two pairs of contacts a , b and c , d which are bridged in succession by sliding bridge members carried by a moving member of insulating material. The moving bridge members are separated by a light spring so that on depressing the button, contacts a and b are first connected and are followed by the connection of contacts c and d . Similarly on releasing the button, contacts c and d are opened first.

The sequence of events occurring during the switching on and off of the lamp will now be described. Operation of the press button switch first closes contacts a and b and thus relay F is energised by its coil which is connected in series with limiting resistance R_2 across the 110 volt supply. The circuit between the terminals T_2 of relay F is closed and energizes the operating coil of the main contactor O which closes and places the 110 volt supply across the lamp in series with H. F. choke N.

In order to obtain the necessary inductance in a relatively small space, the choke N is wound with relatively fine wire which would not be capable of carrying the main discharge current of the lamp. In series with the choke is the operating coil M of an electromagnetic switch S₃ which, when the main discharge current flows through the lamp, closes its contacts and short-circuits the choke N.

Continued pressure on the press button causes contacts c and d to be closed with the result that operating coil E is energised and the switch D is operated to close the contacts S₁, the contacts S₂ being opened.

The closing of S₁ results in condenser C₁, which is of $5000 \mu f$. capacity, being charged up from the 110 volt supply through the current limiting resistance R₃.

On releasing the push button contacts, c and d are first opened and the operating coil E is de-energised with the result that the mercury switch changes over under the influence of its return spring, the contacts S₂ being closed and the contacts S₁ opened so that the charged condenser C₁ is connected directly across the low impedance primary winding of the transformer T, through which flows as a result a very heavy surge of current, with a peak value which may

reach 2500 amps. This heavy current surge initiates the events causing the striking of the lamp, to be described later.

Consider now the conditions which exist after the push button has been released and the lamp has struck. The circuit between the terminals T_2 of relay F is closed and the contacts S₂ are held closed by the return spring of the switch D. If now the push button is operated for a second time, the contacts a and b which close first, energise the coil of relay F and now cause this relay to release, so breaking the circuit between the terminals T_2 , and de-energise the main contactor O which releases and disconnects the 110 volt supply from the lamp and charging circuit. Thus no charge is given to condenser C₁ and the switch D is not operated when the contacts c and d close at the end of the push button travel. Also the lamp A, if it is running, will be extinguished. Release of the push button and de-energisation of relay F has no further effect.

The transient surge through the primary of T, referred to above, is stepped up by the action of the transformer and a voltage impulse of about 26 kv. in magnitude appears across the secondary winding. The condenser C₂ of capacity $.007 \mu f$. is thus charged up to this value through chokes L₁ and L₂. When the voltage across C₂ reaches a critical value (about 20 kv.) the spark gap G breaks down and the lamp A and the inductance L₃ in series are connected across the charged condenser C₂. The interelectrode space of the lamp then breaks down and a spark discharge passes. Condenser C₂ is then effectively discharging through the inductance L₃ connected in series therewith. The values of inductance L₃ and capacity C₂ are such that the discharge is oscillatory in nature, having a frequency of approximately 345 kc./s. The arc discharge across the lamp electrodes is also of the same form, the peak values of voltage and current reached at the commencement of the train of oscillation, being about 20 kv. and 8 amps. respectively. The damping of the circuit is such that after about 35 μ secs. the peak amplitude of the oscillation will have fallen to a few thousand volts. The high frequency oscillation which occurs during the discharge of condenser C₂ is prevented from passing back through the transformer secondary winding by virtue of the two chokes L₁ and L₂. Similarly the main supply which is connected across the lamp is prevented from short circuiting the high frequency oscillation by virtue of the choke N. The condenser C₅ and rectifier X are included to protect the main supply circuit from any small leakage of high frequency current which may unavoidably pass the choke N.

At some time after the high frequency oscillatory discharge has commenced, the main mercury vapour arc discharge will be struck and maintained, the high frequency arc then being extinguished. When the main discharge current of the lamp flows through the operating coil M of the switch S₃ the choke N is short-circuited so that it has not to carry the main current except for the brief period necessary to effect operation of the short circuiting switch. The choke N has not therefore to be designed to carry the full load current of the lamp for any extended period.

70 I claim:

1. An operating circuit for a high pressure vapor electric discharge lamp adapted to operate normally from a direct current source and having characteristics such that on starting operation with any combination of internal temperature

and pressure, which may occur, a high frequency discharge must be maintained between the electrodes of the lamp for a predetermined minimum time before the normal direct current discharge can start and be maintained, said circuit comprising: a first pair of terminals for connection to the electrodes of the lamp; a resonant circuit electrically connected across said first pair of terminals; a high voltage pulse generator; a switching means connected in circuit with said pulse generator and causing a substantially unidirectional high voltage pulse to be generated on each occasion on which it is operated; means for applying the output of said pulse generator to the resonant circuit, the resonant circuit having a decrement and resonant frequency such that on application of a pulse from the said pulse generator when the lamp is connected to the first pair of terminals, a high frequency discharge will be maintained in the lamp for at least said predetermined minimum time; a second pair of terminals for connection to the direct current source for use in normal operation of the lamp; and circuit means completed on operation of said switching means for electrically connecting said second pair of terminals to said first pair of terminals.

2. An operating circuit for a high pressure vapor discharge lamp according to claim 1 in which said circuit means includes at least one high frequency choke and relay means having a winding connected in series with the choke and a contact operated when the current in said winding reaches a value slightly less than the normal discharge current of the lamp, to short circuit said choke.

3. An operating circuit for a high pressure vapor electric discharge lamp adapted to operate normally from a direct current source and having characteristics such that on starting operation with any combination of internal temperature and pressure, which may occur, a high frequency discharge must be maintained between the electrodes of the lamp for a predetermined minimum time before the normal direct current discharge can start and be maintained, said circuit comprising: a first pair of terminals for connection to the electrodes of the lamp; a resonant circuit electrically connected across said first pair of terminals; a second pair of terminals for connection to a direct current source; a capacitance; a voltage step-up pulse transformer having a primary and a secondary winding; a switching means, said switching means being connected in circuit with said second pair of terminals, said capacitance and said primary winding, for sequentially on operation, connecting said capacitance across said second pair of terminals to charge substantially to the voltage of the source connected thereto, disconnecting said capacitance from said second pair of terminals without discharging it, and connecting said capacitance across the primary winding to discharge through it; means connecting the secondary winding across part at least of the resonant circuit, the resonant circuit having a decrement and resonant frequency such that on application of a substantially unidirectional high voltage pulse thereto on discharge of said capacitance through the primary winding when the lamp is connected to said first pair of terminals, a high frequency discharge will be maintained in the lamp for at least said predetermined minimum time; a third pair of terminals for connection to the direct current source for use in normal operation of the

lamp; and circuit means completed on operation of said switching means for electrically connecting said third pair of terminals to said first pair.

4. An operating circuit for a high pressure vapor discharge lamp according to claim 3 in which said circuit means includes at least one high frequency choke and relay means having a winding connected in series with the choke and a contact operated when the current in said winding reaches a value slightly less than the normal discharge current of the lamp, to short circuit said choke.

5. An operating circuit for a high pressure vapor electric discharge lamp according to claim 3 in which said switching means comprises: a push button switch having a first and a second pair of contacts which are closed on operation in that order and open in that order on release; a first relay means connected in circuit with said first pair of contacts across said third pair of terminals for completing and breaking the connection between said third and first pairs of terminals of alternate occasions of closing said first pair of contacts; a second relay means and a changeover switch, said second relay means being connected in circuit with said second pair of contacts across said third pair of terminals, changing the switch from a first to a second position on energization and back on de-energization and said changeover switch in said first position connecting the capacitance across the said third pair of terminals and in said second position connecting the capacitance across the said primary winding.

6. An operating circuit for a high pressure vapor electric discharge lamp adapted to operate normally from a direct current source and having characteristics such that on starting operation with any combination of internal temperature and pressure, which may occur, a high frequency discharge must be maintained between the electrodes of the lamp for a predetermined minimum time before the normal direct current discharge can start and be maintained, said circuit comprising: a first pair of terminals for connection to the electrodes of the lamp; a resonant circuit electrically connected across said first pair of terminals, said resonant circuit including a capacitance, an inductance and a spark gap connected in series; a second pair of terminals for connection to a direct current supply; a further capacitance; a voltage step-up pulse transformer having a primary and a secondary winding; a switching means, said switching means being connected in circuit with said second pair of terminals, said further capacitance and said primary winding for sequentially on operation connecting said further capacitance across said second pair of terminals to charge substantially to the voltage of the supply connected thereto, disconnecting said further capacitance from said second pair of terminals without discharging it, and connecting said further capacitance across the primary winding to discharge through it; means connecting the secondary winding across the capacitance in said resonant circuit, the resonant circuit having a decrement and resonant frequency and the spark gap having a break-down potential such that on application of a substantially unidirectional high voltage pulse across the capacitance therein on discharge of said further capacitance through the primary winding when the lamp is connected to the first pair of terminals, said spark gap will break down when the capacitance is

charged to a substantial proportion of the peak pulse potential and a high frequency discharge will be maintained in the lamp for at least said predetermined minimum time; a third pair of terminals for connection to the direct current source for use in normal operation of the lamp; and circuit means completed on operation of said switching means for electrically connecting said third pair of terminals to said first pair.

7. An operating circuit for a high pressure vapor electric discharge lamp adapted to operate normally from a direct current source and having characteristics such that on starting operation with any combination of internal temperature and pressure which may occur a high frequency discharge must be maintained between the electrodes of the lamp for a predetermined minimum time before the normal direct current discharge can start and be maintained, said circuit comprising: a first pair of terminals for connection to the electrodes of the lamp; a resonant circuit electrically connected across said first pair of terminals; a second pair of terminals for connection to the direct current source for use in normal operation of the lamp; a direct current circuit for normal operation of the lamp between said second pair of terminals and said first pair of terminals, said circuit including an electrically controlled contact making device for opening and closing the circuit; a pulse generator for generating substantially unidirectional high voltage pulses; switching means electrically connected to said second pair of terminals for controlling the said contact making device and the pulse generator by applying energy from the source connected to the second pair of terminals in operation, to cause the pulse generator to generate a pulse on operation of the contact making device to close the operating circuit for the lamp; and means for applying the output of said pulse generator across part at least of the resonant circuit, the resonant circuit having a decrement and resonant frequency such that on application of a pulse from the pulse generator, when the lamp is connected to the first pair of terminals, a high frequency discharge will be maintained in the lamp for at least said predetermined minimum time.

8. An operating circuit for a high pressure vapor electric discharge lamp according to claim 7 in which said operating circuit for the lamp includes at least one high frequency choke and relay means having a winding connected in series with the choke in the normal direct current discharge path of the lamp and a contact operated when the current in said winding reaches a value slightly less than the normal discharge current of the lamp to short circuit said choke.

9. An operating circuit for a high pressure vapor electric discharge lamp adapted to operate normally from a direct current source and having characteristics such that on starting operation with any combination of internal temperature and pressure which may occur a high frequency discharge must be maintained between the electrodes of the lamp for a predetermined minimum time before the normal direct current discharge can start and be maintained, said circuit comprising: a first pair of terminals for connection to the electrodes of the lamp; a resonant circuit electrically connected across said first pair of terminals; a second pair of terminals for connection to the direct current source for use in normal operation of the lamp; a direct current

circuit for normal operation of the lamp between said second terminals and said first terminals, said circuit including an electrically controlled contact making device for opening and closing the circuits; a capacitance and a voltage step-up pulse transformer having a primary and a secondary winding; a first switching means; a second switching means electrically connected to said second pair of terminals for controlling the contact making device and said first switching means on operation of the contact making device to close the operating circuit for the lamp, said first switching means being arranged on operation sequentially to connect said capacitance across said second pair of terminals to charge substantially to the voltage of the source connected thereto in operation, to disconnect said capacitance from said second pair of terminals without discharging it, and to connect said capacitance across the primary winding of the pulse transformer to discharge through it; means connecting the secondary winding of the pulse transformer across part at least of the resonant circuit, the resonant circuit having a decrement and resonant frequency such that on application of a substantially unidirectional high voltage pulse on discharge of said capacitance through the primary winding, when the lamp is connected to the first pair of terminals, a high frequency discharge will be maintained in the lamp for at least said predetermined minimum time.

10. An operating circuit for a high pressure vapor electric discharge lamp according to claim 9 in which said operating circuit for the lamp includes at least one high frequency choke and relay means having a winding connected in series with the choke in the normal direct current discharge path of the lamp and contact operated when the current in said winding reaches a value slightly less than the normal discharge current of the lamp to short circuit said choke.

11. An operating circuit for a high pressure vapor electric discharge lamp according to claim 9 in which said second switching means comprises a push button switch having a first and a second pair of contacts which are closed on operation in that order and open in that order on release, and a first relay means connected in circuit with said first pair of contacts across said second pair of terminals for operating said contact making device so as to close and open the operating circuit for the lamp on alternate occasions of closing said first pair of contacts; and said first switching means comprises a second relay means and a changeover switch, said second relay means being connected in circuit with said second pair of contacts across said second pair of terminals and causing the changeover switch to move from a first to a second position on energization and back on de-energization and said changeover switch in said first position connecting the capacitance across the said second pair of terminals and in said second position connecting the capacitance across the said primary winding.

12. An operating circuit for a high pressure vapor electric discharge lamp adapted to operate normally from a direct current source and having characteristics such that on starting operation with any combination of internal temperature and pressure which may occur a high frequency discharge must be maintained between the electrodes of the lamp for a predetermined minimum time before the normal direct cur-

rent discharge can start and be maintained, said circuit comprising: a first pair of terminals for connection to the electrodes of the lamp; a resonant circuit electrically connected across said first pair of terminals, said resonant circuit including a capacitance, an inductance and a spark gap connected in series; a second pair of terminals for connection to the direct current source for use in normal operation of the lamp; a direct current circuit for normal operation of the lamp between said second terminals and said first terminals, said circuit including an electrically controlled contact making device for opening and closing the circuit; a capacitance and a voltage step-up pulse transformer having a primary and a secondary winding; a first switching means; a second switching means electrically connected to said second pair of terminals for controlling the contact making device and said first switching means on operation of the contact making device to close the operating circuit for the lamp, said first switching means being arranged on operation sequentially to connect said capacitance across said second pair of terminals to charge substantially to the voltage of the source connected thereto in operation, to disconnect said capacitance from said pair of terminals without discharging it, and to connect said capacitance across the primary

5
